[57] **CLAIM**

The ornamental design for safety locking device for garage doors, as shown and described.

DESCRIPTION

FIG. 1 is a perspective view of a safety locking device for garage doors showing our new design;

FIG. 2 is an end elevational view thereof;

FIG. 3 is a rear elevational view thereof;

FIG. 4 is a cross-sectional view thereof taken along line 4—4 in FIG. 3;

FIG. 5 is a front elevational view thereof in open condition;

FIG. 6 is a perspective view of a safety locking device for garage doors showing a second embodiment of our new design;

FIG. 7 is an end elevational view of FIG. 6;

FIG. 8 is a rear elevational view of FIG. 6;

FIG. 9 is a cross-sectional view of FIG. 6 taken along line 9—9 in FIG. 8;

FIG. 10 is a front elevational view of FIG. 6 in open condition.
